[57] CLAIM

The ornamental design for a spray bottle, as shown and
described.

DESCRIPTION

FIG. 1 is a perspective view of the bottle showing our
new design;

FIG. 2 is a front view thereof, the undisclosed opposite
side being identical;

FIG. 3 is a side view thereof, the undisclosed opposite
side being identical;

FIG. 4 is a bottom view thereof;

FIG. 5 is a top view thereof;

FIG. 6 is a perspective view thereof, with the cover
removed for clarity of illustration;

FIG. 7 is a front view of FIG. 6, the undisclosed opposite
side being identical;

FIG. 8 is a side view of FIG. 6, the undisclosed opposite
side being identical;

FIG. 9 is a top view of FIG. 6;

FIG. 10 is a perspective view of a second embodiment
of the bottle as disclosed in FIG. b 1;

FIG. 11 is a front view of FIG. 10, the undisclosed
opposite side being identical;

FIG. 12 is a perspective view of FIG. 10, with the cover
removed for clarity of illustration; and,

FIG. 13 is a front view of FIG. 12, the undisclosed
opposite side being identical.
